UNITED STATES PATENT OFFICE

ROBERT C. SCHEMML, OF UNION CITY, INDIANA

FINISHING WELT

Application filed February 7, 1930. Serial No. 426,643.

My invention relates to finishing welts, that is to say, to that type of trimming strip which is extensively used to cover the meeting edges of upholstery fabric of furniture and to trim the edges of covering materials in automobile bodies and tops which is characterized by a strip of covering material folded upon itself to provide at least one longitudinal bead or looped portion containing a filler of appreciable thickness.

More particularly, my invention relates to a welt having a novel type of filler for the beads of the enclosing fabric. According to standard practice finishing welts of the types to which my invention pertains are constructed to be relatively flat, having an appreciable thickness which is considerably less than the width of the strip. A preferred design employs a substantially half round filler for one of the beads of the welt, so that the width of this filler is at least twice as great as its thickness or height. The filler is commonly disposed in its bead with its flat, plane face down against the base of the welt and its curved or cylindrical surface uppermost, and since it is necessary in practically every installation to dispose the welt about a short curve in the plane of a straightaway length of welt, serious difficulty has been encountered with these welts of the prior art because of the inherent tendency of the filler to buckle or pucker in its curved portions.

Various attempts have been made to remedy this difficulty, the most successful of which prior to my present invention has been by way of forming the filler out of rubber, the resilience of which is well adapted to negotiate short curves with a minimum of buckling. Apart from its liability to harden and deteriorate with age, rubber has been found to be functionally a successful and efficient welt filler material, but commercially it has not been a success because of its high cost.

It is an object of my present invention to provide a welt having fillers formed of a material which is capable of disposition about curves of an exceedingly short radius without buckling and which may be produced at a minimum cost.

It is a further object to provide a welt having fillers exhibiting these desirable curving characteristics and also having the hardness and smoothness of surface necessary to give firmness and body to the welt.

Other and further objects and advantages of welts constructed in accordance with the principles of my present invention will be sufficiently apparent as the description proceeds.

One form of embodiment of my invention is illustrated in the accompanying drawings and described in the following specification, and the invention will be hereinafter more particularly pointed out in the appended claims.

In the drawings which form part of this application for Letters Patent, and in which like reference characters designate the same parts in the several views,

Figure 1 is a perspective view, with one end in cross section, of a short section of the tubular structure the formation of which constitutes an initial step in the production of my new welt filler;

Fig. 2 is a similar view of a completed welt filler;

Fig. 3 is a similar view of a completed welt filler of a different contour, which in one form of welt is adapted to coact with the type of filler shown in Fig. 2; and

Fig. 4 is a perspective view, with one end in section, of a finished welt formed out of the novel fillers.

Referring now to the drawings, 1 indicates one of the strands of twisted fibrous material, preferably paper, which constitute the component elements of my novel filler. These strands are formed by tightly twisting relatively narrow strips of paper into a substantially cylindrical shape, and then a plurality of the strands are plaited or braided into the tubular structure shown in Fig. 1. The number of the strands to be used varies of course with their individual diameters, and with the size of the filler which is to be made.

The tubular structure of Fig. 1 which may or may not be treated with a suitable sizing compound, is formed directly into the desired type of filler. In Figs. 2 and 3 I have illus-

trated the two shapes of filler which are necessary to the production of the welt which forms the subject of United States Letters Patent No. 1,743,624, issued to me on January 14, 1930. It will be noted that these fillers are of different sizes and cross sectional contours, one being relatively large and half round in section, and the other being smaller and of what might be termed kidney shaped cross sectional configuration. I have shown these two fillers merely by way of exemplification of my invention in one form of embodiment, and it is to be understood that their specific shape is immaterial to the present invention, since the particular form of the filler is dependent only upon the design of the welt in which it is to be used, and is achieved by using different dies, rollers or other means in the filler forming operation which will now be described.

The required shape of the finished filler is attained by forcing the tubular structure of Fig. 1 through a suitable die after the manner of well understood wire forming or rubber extruding operations. In the alternative, the tubular stock may be passed between pressure rollers having their surfaces preferably shaped to give the desired form to the issuing product. Thus, if the filler shown in Fig. 2 is to be produced, one of the rollers will be a true cylinder, and the cooperating roller will be provided with a concave surface. To form the filler of Fig. 3 one convex and one concave roller are used, and so on, as will be readily understood. The specific manner of converting the tube of Fig. 1 into the desired filler forms no part of my present invention, and it is to be understood that any practical and operative means or method may be employed.

In addition to giving the required shape to the resulting filler, one effect of the forming operation is to compact the tubular structure by compressing its component strands into intimate contact with each other, to form a relatively hard and smooth surfaced filler, as shown in Figs. 2 and 3. Such a filler is well adapted to be enclosed in a covering strip 2 of any well known welt fabric, as shown in Fig. 4, to provide a completed welt structure, the hardness of the compressed assembly of strands giving the desired firm body to the welt, and the substantially smooth surface of the filler providing a practically unbroken foundation for the covering material, so that the outer appearance of the welt containing my braided fillers is in all respects equal to that of welts made with molded or twisted single piece fillers.

It will be apparent that all the advantages of the old type of welts having single piece fillers inhere in my new welt when used along a straightaway. It is, however, around turns of short radius that the peculiar advantages of my new welt appear. When

the welt is disposed about such a turn, the theretofore closely contacting strands move relatively to each other to a very slight degree, so that the interlacing about the inner edge of the curve opens up, as it were, to a small extent. In other words, without any apparent stretching or compressing of individual strands, the strands seem automatically to rearrange their relative positions by sliding on each other to dispose themselves about the curve without appreciably increasing the area of any cross section through the curved portion.

The practical result of this manner of operation is to eliminate the highly objectionable buckling and puckering of the welt about short curves that characterizes welts made with one piece solid fillers of inexpensive, non-resilient material and to give to the welt all the efficiency in curve turning ability that has heretofore been attained only by the use of expensive rubber fillers.

While it is true that the problem of puckering and buckling around short curves is encountered more especially in welts having fillers which are greater in width than in thickness, and therefore fillers made according to the teachings of my present invention are more particularly adapted to use in such welts, it is nevertheless to be understood that my invention in its broader aspects contemplates the inclusion in any kind of welt of a filler within the broad scope and purview of the appended claims.

Having thus described my invention what I claim and desire to secure by Letters Patent is:

1. A bead filler for finishing welts and the like comprising a plurality of individual strands of relatively hard material braided together and compacted to form a body having a relatively hard and smooth surface, the individual strands being capable of slight relative sliding movement whereby the braided assembly "opens up" along its inner edge when the filler is flexed around a curve.

2. A bead filler for finishing welts and the like comprising a plurality of relatively hard individual strands of tightly twisted fibrous material braided together and compacted to form a body having a relatively hard and smooth surface, the individual strands being capable of slight relative sliding movement whereby the braided assembly "opens up" along its inner edge when the filler is flexed around a curve.

3. A bead filler for finishing welts and the like comprising a plurality of relatively hard individual strands of tightly twisted paper braided together and compacted to form a body having a relatively hard and smooth surface, the individual strands being capable of slight relative sliding movement whereby the braided assembly "opens up" along its

inner edge when the filler is flexed around a curve.

4. The method of making a bead filler for finishing welts and the like which consists in braiding together a plurality of individual strands to provide a substantially tubular hollow assembly, and then subjecting the braided assembly to pressure to compact the strands together into a hard, resistant and smooth surfaced body having the contour of a welt filler.

5. The method of making a bead filler for finishing welts and the like which consists in twisting a strip of paper to form a relatively hard round cord, braiding together a plurality of such cords to provide a substantially tubular hollow assembly, and then subjecting the assembly to pressure to compact the strands together into a relatively hard, resistant and smooth surfaced body having the contour of a welt filler.

6. The method of making a bead filler for finishing welts and the like which consists in braiding together a plurality of relatively hard strands to provide a substantially tubular hollow assembly, and then subjecting the assembly to pressure to form a solid, relatively hard, smooth surfaced, half-round body.

In testimony whereof I affix my signature.

ROBERT C. SCHEMMEL.
